UNITED STATES PATENT OFFICE.

PIERRE SALVAT, OF SAN FRANCISCO, CALIFORNIA.

DESIGN FOR A DRESSING TABLE.

Application filed December 5, 1928. Serial No. 29,125. Term of patent 3½ years.

To all whom it may concern:

Be it known that I, PIERRE SALVAT, a citizen of France, residing in the city and county of San Francisco, and State of California, have invented a new, original, and ornamental Design for a Dressing Table, of which the following is a specification, reference being had to the accompanying drawing, forming a part thereof.

Fig. 1 is a plan view, and Fig. 2 is a front perspective view of the dressing table, showing my new design.

I claim:

The ornamental design for a dressing table as shown.

PIERRE SALVAT.
